UNITED STATES PATENT OFFICE.

VICTOR NIVOIS, OF BROOKLYN, NEW YORK.

CONTAINER.

1,156,019.

Specification of Letters Patent. Patented Oct. 5, 1915.

Application filed September 4, 1914. Serial No. 860,191.

To all whom it may concern:

Be it known that I, VICTOR NIVOIS, a subject of the President of France, residing at Brooklyn, in the county of Kings and State of New York, have invented new and useful Improvements in Containers, of which the following is a specification.

This invention relates to containers, and particularly to containers for articles which are to be carried in the pocket.

While the invention is applicable to many different articles, I have described it in the following specification as applied to a container for cigarettes.

5 A principal object of the invention is to produce a container which is very simple in construction and which can be very economically manufactured.

The invention is particularly applicable to that class of containers which embody in their construction an inner holder which holds the articles such as cigarettes and presents them in an upright position if the container is opened, or laid open upon a horizontal support such as a table.

One of the objects of the invention is to produce a container of this type having an improved form of holder which is very simple and economically manufactured, and 30 which holds the cigarettes in such a way as to increase the effective volume of the container when closed.

A further object of the invention is to provide a container which can be readily produced and particularly which can be readily filled with cigarettes or other articles.

40 A further object of the invention is to provide an arrangement for yieldingly retaining the cigarettes or other articles in the holder.

Further objects of the invention will appear more clearly hereinafter.

The invention consists in the general combination of parts and those features and details hereinafter described, all of which contribute to produce an efficient container.

A preferred embodiment of my invention will be particularly described in the following specification, while the broad scope of my invention will be pointed out in the appended claims.

In the drawings: Figure 1 is a perspective of a container embodying my invention and representing the invention as ap-

plied to a cigarette case. Fig. 2 is a vertical section through the container illustrated in Fig. 1. Fig. 3 is a perspective showing this container in its closed position. Fig. 4 is a plan showing the preferred form of blank 60 from which the holder of the container may be readily formed. Fig. 5 is a longitudinal vertical section showing another form of container for cigarettes embodying the invention. Fig. 6 is a perspective showing this other form of container in its closed position.

Referring more particularly to the parts, 10 and 11 represent two members which are hingedly connected together on the line 12. 70 These two members 10 and 11 are preferably formed integral with each other and are slightly dished so that when they are swung together on their hinge connection at 12, their edges 13 meet continuously so as to inclose a space in which the holder 14 is received. This holder 14 is preferably of box form and may be most conveniently formed from a blank 15 of the form illustrated in Fig. 4. The blank 15 is an elongated strip 80 preferably formed with four score lines 16 at which the blank may be folded to form the corners of the holder, and the parts of the blank which produce the side walls 17 of the holder are of greater depth than the narrower parts 18 and 19 which form end walls 20 of the holder. In this way, the side walls 17 present outwardly extending integral flaps 21 and these flaps are bent outwardly and attached in any suitable manner, 90 as by means of an adhesive, to the inner faces of the members 10 and 11 at the points 22 on opposite sides of the hinge connection 12, preferably as indicated in Fig. 2. The members 10 and 11 are most conveniently 95 formed of paper pressed to the desired dished-shape, and these two members 10 and 11 are preferably made integral with each other by employing a single blank of simple rectangular form properly scored by a 100 transverse line at the hinge connection 12. One or both of the opposite walls 17 are preferably provided with tongues 23 which may, if desired, be integral with the side walls and struck from the material thereof 105 so as to project slightly inwardly and downwardly preferably in the manner illustrated in Fig. 1. These tongues tend to exert pressure on the cigarette 24 in the holder and yieldingly hold them in place. In forming 110

the holder, the end portions 19 may overlap to form the end wall 20, as illustrated in Fig. 1.

In order to protect the cigarettes from direct contact with the tongue or tongues, and also to facilitate the filling of the holders with the cigarettes, I prefer to provide a protecting sheet 25 which is looped at its lower edge where it passes under the lower ends of the cigarettes, and the sides of this sheet extend up on both sides of the cigarettes preferably above the mouth of the holder. This protecting sheet may be made of light paper, foil, or both foil and paper. Evidently the paper folder 25 imparts the pressure from the tongue to the cigarettes and prevents the sharp edge of the tongue from injuring any cigarette when it is withdrawn. This folder sheet is also very useful in facilitating the filling of the holder, for the proper number of cigarettes may be placed together in the folder sheet and then inserted bodily in the holder as will be readily understood. When the container of this form is closed, it will be evident that the lower ends of the cigarettes may project through the bottomless holder 14 and the lower ends of the cigarettes lie near the hinge connection 12 which connects the members 10 and 11.

In Figs. 5 and 6, I have illustrated another embodiment of the invention in which the container is of a more common box form and which, when the container is closed, presents substantially the appearance of an ordinary cigarette box. In this form of the invention, I provide two members 26 and 27, the latter of which is substantially of the form of the body of a neck box, the main wall 26^a of the lid section being preferably formed integral with the main wall 27^a of the body section, said main walls being connected by an integral strip 28 which forms the end wall of the container when closed. At the point of connection between the strip 28 and the main walls, score lines 29 are formed which facilitate the opening and closing of the container. The body section 27 presents side walls 30 and an end wall 31 and the lid section similarly presents side walls 32 and an end wall 33. In this form of container, the holder 34 is of substantially the same form as that illustrated in Figs. 1 to 3, that is, the side walls 35 are preferably of greater depth than the end walls of the holder so that they present flaps 36 which may be bent outwardly and secured by an adhesive or other means to the inner faces of the main walls 26^a and 27^a. In this form of the invention, the holder 34 is also bottomless and the holder, if desired, may also embody substantially the same features illustrated in Figs. 1 to 4.

It is understood that the embodiment of the invention described above is only one of

the many embodiments or forms the invention may take and I do not wish to be limited in the practice of the invention, nor in my claims, to the particular embodiment set forth.

What I claim is:

1. A container consisting of a pair of hingedly connected members adapted to close together so as to inclose a space therebetween, constructed to open out and lie extended upon a horizontal support, a bottomless holder of box form having side walls, and end walls of a width slightly less than the width of the space inclosed between said members, said holder having flaps at the lower end thereof attached to said members respectively at points removed from the hinge connection therebetween, the lower end of said holder being above the hinge connection between said members when the same are closed together, and arranged to support a plurality of cigarettes lying within said holder with the lower ends thereof projecting through the bottomless lower end of said holder, and lying adjacent to the hinge connection between said members.

2. A container for cigarettes consisting of a pair of hingedly connected members, a holder of box form having side walls and end walls for retaining the cigarettes, a side wall of said holder having an integral tongue extending inwardly and having a cigarette engaging edge between the upper and lower edges of said holder to exert a slight pressure upon the cigarettes held within the holder.

3. A container for cigarettes consisting of a pair of hingedly connected members, a holder of box form having side walls and end walls for retaining the cigarettes, a side wall of said holder having an integral tongue struck therefrom extending inwardly to exert a slight pressure upon the cigarettes held within the holder, said side walls of said holder being of greater depth than said end walls to form integral extensions attached to the inner faces of said members.

4. A container consisting of a pair of hingedly connected members, a holder of box form having side walls and end walls for retaining the cigarettes, a side wall of said holder having an integral tongue struck therefrom and extending inwardly to exert a slight pressure upon the cigarettes held within the holder, and a protecting sheet between said tongue and the cigarettes, protecting the cigarettes and imparting the pressure thereto from said tongue.

5. A container consisting of a pair of hingedly connected members, a holder of box form having side walls and end walls for retaining the cigarettes, a side wall of said holder having an integral tongue struck therefrom and extending inwardly to exert a slight pressure upon the cigarettes held

within the holder, and a protecting sheet passing under the lower inner ends of the cigarettes and lying on opposite sides thereof and extending between said tongue and the cigarettes, and imparting the pressure thereto from said tongue.

In testimony whereof I have hereunto set

my hand in presence of two subscribing witnesses.

VICTOR NIVOIS.
